UNITED STATES PATENT OFFICE

91,332

DESIGN FOR A SERVICE STATION

Guy L. Rosebrook, Cranberry Lake, N. J., assignor
to Standard Oil Development Company, a cor-
poration of Delaware

Application August 4, 1933. Serial No. 48,923

Term of patent 14 years

To all whom it may concern:

Be it known that I, GUY L. ROSEBROOK, a citizen of the United States, residing at Cranberry Lake, in the county of Sussex and State of New Jersey, have invented a new, original, and ornamental Design for Service Station, of which the following is a specification, reference being had to the accompanying drawings, forming part thereof.

Fig. 1 is a front elevation of a service station, showing my new design,

Fig. 2 is a side elevation of the same,

Fig. 3 is a perspective view of the service station, and

Fig. 4 is an elevation of the end of the service station opposite to that shown in Fig. 2.

The side of the service station opposite to that shown in Fig. 1 is a blank wall.

I claim:

The ornamental design for a service station, substantially as shown and described.

GUY L. ROSEBROOK,
